UNITED STATES PATENT OFFICE.

FREDERICK HEATH, OF TACOMA, WASHINGTON, ASSIGNOR TO HEATH UNIT TILE COMPANY, OF TACOMA, WASHINGTON, A CORPORATION OF WASHINGTON.

FIREPROOF HOLLOW WALL CONSTRUCTION.

Application filed October 8, 1921. Serial No. 506,234.

To all whom it may concern:

Be it known that I, FREDERICK HEATH, a citizen of the United States, residing at Tacoma, in the county of Pierce and State 5 of Washington, have invented a certain new and useful Improvement in Fireproof Hollow Wall Construction, of which the following is a full, clear, and exact description, reference being had to the accompanying drawings.

This invention relates to a system or method of protecting masonry building walls from damage by fire.

In the construction of building walls of 15 load bearing hollow tile character, it has heretofore been customary, when desired to provide a fireproof structure, to face the walls interiorly with some sort of a protecting means, but such methods usually leave 20 vulnerable spots, that is unprotected areas, which, when subjected to great heat, weaken the wall with the result that the entire wall is endangered.

The general object of this invention therefore, 25 is to provide a protection for a masonry building wall which shall be simple, effective, capable of being furnished and applied very cheaply in comparison to the cost of the wall, and which shall leave no 30 vulnerable point, where the heat may weaken the wall, anywhere in the entire structure.

The invention contemplates particularly 35 use in connection with hollow building wall construction with a view to providing a structure which shall be so completely fireproof that it shall meet with all the requirements of the highest type of fireproof masonry wall construction, as defined by 40 Insurance Underwriter's specifications, building ordinances, etc.

A still further object is to so construct 45 my wall that a complete effective insulation is provided, lining the entire wall and which may be partially or wholly destroyed by fire without in the least impairing the load bearing qualities and characteristics of the main body of the wall. A further object 50 is to so arrange and construct this protection for the body of the wall that it may be completely removed and replaced after a fire at an exceedingly small percentage

of the cost of a new wall and yet provide, when replaced, a wall equivalent in all respects to the original structure.

In carrying out my invention, I have provided a combination of main wall and protection blocks, so arranged and proportioned that the whole may be laid in complete, even, horizontal courses with a minimum 55 of cutting or breaking of blocks. The protection extends around corners, offsets, chases, pilasters, jambs, etc., throughout the wall and even behind the window jambs and under lintels, over window sills, and 60 the like, the whole forming a complete uniform system of construction, being added to the wall with a minimum of expense and providing, when completed, a very workmanlike effective masonry structure.

More specific objects of the invention include the novel means of securing such protection to the main body of the wall, and the arrangement of the fireproof supports for the ends of the floor beams, joists and 65 other supports set into the wall at their ends.

Other objects and novel characteristics will become apparent in the following description which relates to the drawings 70 illustrating a preferred embodiment of my invention, the essential characteristics being summarized in the claims.

In the drawings, Fig. 1 is a fragmentary perspective view of the corner of a wall 75 construction embodying my invention, Fig. 2 is a detail in perspective showing a fireproof support for a floor joist; Fig. 3 is an enlarged vertical transverse section through a plurality of courses of wall and protection showing the method of bonding the protection tile to the wall; Fig. 4 is a fragmentary plan view of a course of a body of the wall and a pilaster construction showing the arrangement of the protection 80 in connection therewith; Fig. 5 is a vertical section through a lintel over a window opening showing the arrangement of the protection at that point; Fig. 6 is a plan of one of the courses and a window jamb showing 85 the arrangement of protection for the wall around the window frame.

The main body of an exemplary hollow tile wall is illustrated in Fig. 1. I have

chosen for this illustration a form of wall construction shown, described and claimed in my Patent No. 1,214,149, granted Feb. 6, 1917. In this structure, each course includes hollow building blocks, providing running bonds and even horizontal mortar beds throughout the entire wall. These courses are shown as made up of three void blocks 1 and single void blocks 2 laid alternately in successive courses in such a manner as to produce vertical alignment of webs, to accomplish a complete series of tiers of vertical load bearing members, and to develop the full strength of horizontal mortar bed.

Such a wall provides the ideal characteristics of a hollow load bearing structure having many advantages from the standpoint of economy of construction, insulating characteristics, solidity of the completed structure, and other valuable features. The walls of this character, however, capable of use in high grade load bearing wall structures have a serious disadvantage if unprotected, in that a fire on the interior of the building, for example, may destroy the first one or two tiers of vertical load carrying members. That is, the application of alternate heat and cold water with resulting expansion and contraction, weakens the wall so that a fire destroys its usefulness and it must be rebuilt.

Even though the wall is largely protected, any vulnerable point might so weaken the wall so as to allow the falling of the entire structure, or to require that it be largely or entirely rebuilt after such a fire. In order to make a complete fire proof construction of this otherwise very economical wall construction, by the use of simple and inexpensive protection, I have chosen to use blocks of the character shown at 10 to completely line the entire wall. For this purpose I may conveniently use what are known as Heath corner and jamb blocks which have been demonstrated to be commercially successful from the manufacturing standpoint, and which preferably have a vertical dimension equivalent to the height of the individual courses, and which may be divided to conveniently fit them in the corners, pilasters, jambs, and like offsets. These blocks are hollowed by voids 11 and the division is facilitated by the narrow slot-like void 12. Such a block is more fully shown and described in my Patent No. 1,403,953 issued January 17, 1922. They may also be used for closing the corners and jambs in the main body of the wall. This permits using a minimum number of shapes of blocks.

As the wall structure is built, I cover the entire interior, course by course, with these blocks 10 in the fashion shown in Fig. 1. The upper portion of the wall indicated at M in Fig. 1, is shown, just before placing

the lining blocks in position. The course N just below shows the upper faces of the protection blocks 10 as completing the upper level of the mortar bed.

Between the courses N and O, are illustrated securing means in the nature of corrugated or roughened metal strips 15 imbedded into the mortar and projecting between adjacent blocks 10. At intervals through the wall structure, I may provide additional supports or an entire series of courses of the blocks 10 by laying metal strips 25 along the entire course of the blocks of the wall and projecting between the courses of the lining blocks 10 as shown on the upper surface of the course in Fig. 1. The effect of these strips, is an additional bonding of the protection blocks to the main body of the wall, but, more particularly, it is to allow the removal of a section of the lining below. Such a strip may be used for example, at each floor, so that a whole story of a building which has been damaged by fire can be repaired by merely replacing this lining, for that story, with the least possible difficulty, and without disturbing the courses of lining blocks above the strip 25 for the story above.

Such strips are placed longitudinally of the courses, in the mortar space and project outwardly sufficiently to afford a support engaging the inner shells of the lining blocks 10.

At 20 are indicated floor beams, carrying the usual floor boards 22, and which have their ends extending into spaces provided by separating the ends of blocks in the wall, using short blocks as indicated at 1^a in the course. The ends of the floor beams 20 are preferably chamfered or beveled as indicated at 21 and they project into the wall the distance of one of the half blocks 2^a. A small block 5^a may be placed over the blocks 1 to continue the support for the mortar bed to reduce to a minimum the interruption of a mortar bed support opposite the ends of these beams, and yet permit the beams to fall downwardly when burned away at the middle portion thereof without displacing any of the blocks in the wall, or straining the same. It will be noted that the lining blocks are continued between the wall and the beams 20 which are adjacent the wall as at the right in Fig. 1.

These beam end openings through the protection lining are too small to endanger the wall. Even this may be avoided by using beam supports such as shown in Fig. 2. These supports are of metal having a carrying surface 50 braced by side pieces 51 integral with a vertical member which is also integral with a wing 52 lying in the mortar bed.

The fire protection of the body of the wall is continued around openings such as

windows and doors, as stated, to leave no vulnerable point. An example of the method of accomplishing this, is illustrated at the window opening, a portion of which is shown at the left of Fig. 1, where one of the courses extends across the window opening with a lintel construction, such for example as is illustrated in my prior Patent No. 1,244,328, October 23, 1917. This lintel continues the course in which it is placed, extending over the opening at each side thereof, and as shown consists of alternately arranged blocks 1 and 2, and filled with concrete or like substance as at 32 while rods 31 extend through the lower portion of the voids so filled to give the beam strength.

In Fig. 5, it will be noted this lintel is shown as sectioned with the outside of the wall at the right of this figure. Below the lintels the protection is continued by the blocks 10 placed horizontally as shown. These may be supported in any convenient fashion as by short rod hooks or wires 34 attached to bridge like washers 35 in one case, or to strips 36 placed similarly to the strips 25 and having openings through which the supporting rods 34 may project. The lower ends of these rods 34 are provided with hooks to engage in suitable voids of the blocks 10. In this figure is shown a full width block 10 and the two thirds section of such a block, one portion being broken away to fit within the width of the wall plus the lining blocks, which appear at the left of Fig. 5.

The window frame may be fitted inside of the lining as indicated at 40. 41 indicates the glass. An identical construction may serve to properly protect the wall at the door openings.

Fig. 6 is a horizontal section showing the top of a course consisting of the blocks 1 and 2 terminating at the side of the window opening, and here the blocks serve the function of forming the window jamb as well as projecting the wall. The blocks are shown as overlapping slightly, leaving an opening filled with a third section block set vertically. These may be suitably bonded into place by turning blocks of every other course inwardly into the wall as may be desired.

In Fig. 4, is illustrated a method of extending a lining around pilasters and similar offsets in the wall. In this figure the section consists of a plan of the course showing a wall, the width of one of the double blocks 1 to which the pilaster is bonded. It is shown as built of specially constructed pilaster blocks such as illustrated, described and claimed in my patent application, No. 378,056. At the right and the left of the figure the blocks 10 are shown as coming up to the pilaster,

along the face of the wall and then at each side thereof are blocks turned inwardly at right angles to the wall. Along the inner side, the blocks are arranged to fit around and cover the pilaster at each course. If desired, retaining straps 15, may be used at frequent intervals in the pilasters embedding the same into the horizontal mortar beds.

In Figs. 3 to 6 inclusive, the inner side of the wall is shown as plastered, although if the tile are to present the finish as shown in Fig. 1, it is only necessary to turn the smooth side of the blocks 10 outwardly, leaving the corrugated or grooved side inwardly.

From the foregoing description, it will be seen that I have provided a fireproof wall structure, which if attacked by fire, resists it after the manner of the highest grade fireproof structures, because the fire must first attack the plaster if any and destroy it before affecting the blocks behind it. If no plaster is used the fire and subsequent applications of water may result in cracking the outer shells of the blocks 10. Even though part of these outer shells falls away under the alternate application of heat and water, the inner part of these shells still protects the wall. That is, space corresponding to the mortar joint behind each block 10, provides actual insulating between the parts subjected to the fire and the load bearing tiers of the webs and shells of the wall, even where only the inner shells of the blocks 10 remain.

After such a fire, the building remains intact, because opposite the floors, etc., this protection has left no vulnerable spot where the wall is damaged and to repair the building, the only expense required is to remove the damaged lining blocks 10, and replace them and refinish the interior. Lower rates of insurance can be obtained on such a structure. The cost of this protection to the body of the structure is a very slight initial cost and although the entire interior of the building may be destroyed by a conflagration, the walls remain intact and need be only relined to completely repair the wall structure of the building.

Plaster linings and blocks having additional shells intended to be cracked off by fire, have been used for fireproofing such a hollow wall, but where such protection constitutes an integral part of the blocks of the body of the wall, to repair the wall making it fireproof as it was originally intended, requires rebuilding of the damaged portions of the wall, if not the entire structure. With my device the worst that any fire attacking the lining or protected surface can do to the wall is to destroy a part or all of the protection means, but the body of the wall remains intact, thus

retaining its full strength to carry the load, and at no time impairing or endangering the structure.

Even where plaster protections have been used, or linings of furring and the like are used in wall structures, they are not adapted to be built, with the wall structure behind floor beams, joists and partitions, and thus leave no vulnerable points which fire may attack. By this system, I am able to comply with various requirements of established building ordinances enacted to promote fire protection and fire-proofing of building, and still permit the building of the interior of the building of inflammable material without endangering the walls.

A protection for the building is afforded which is exceedingly simple and economical to construct, which is very effective in protecting the wall and it can be replaced to reline the wall at a minimum of expense, for example, two or three percent of the cost of the building.

Having thus described my invention, I claim:

1. In a fireproof building structure, the combination of a main load bearing wall consisting of hollow tile, floors within the structure, and a fireproof lining for the wall extending past the floors and extending around the normally exposed portions of the wall at window and door openings.

2. A fireproof building structure, the walls of which are constructed of hollow tile arranged to provide load bearing characteristics, and having floors therein supported by the wall, and a fireproof lining for the wall extending continuously adjacent the floors whereby vulnerable points subject to injury by fire are eliminated.

3. In a fireproof structure, the combination with load bearing hollow walls of fire resisting material and floors carried and supported by said walls of a replaceable fire proof lining entirely coextensive with the wall portions adjacent the floors and extending continuously with the lining for the said wall portions around the inner faces of openings such as windows and doors.

4. A fireproof structure consisting of a load bearing hollow tile wall arranged in courses, a series of courses of hollow blocks forming a fireproof lining for such wall constituting a component part of the wall structure and means extending into the wall for securing the lining blocks spaced apart from the wall, said lining extending past the floors of the structure.

5. A fireproof structure, consisting of a load bearing hollow wall arranged in courses with webs and shells in alignment, and a lining added to the wall and forming a part of the composite structure and con-

sisting of blocks arranged in courses corresponding in height to the courses of tile in the load bearing wall bonded to the wall and having voids extending therethrough, and said blocks being spaced from the adjacent shells of the blocks of the wall.

6. A fireproof structure, consisting of a load bearing hollow wall arranged in courses, and a protective lining added to the wall and forming a part of the composite structure, and consisting of blocks arranged in courses and having voids extending therethrough, and said blocks being spaced from the adjacent shells of the blocks of the wall, and means for securing said lining blocks to the body of the wall, and said protective lining thus formed extending continuously past the floors of the structure.

7. A fireproof wall structure, for a building consisting of hollow load bearing tile walls in which the tile are arranged in horizontal courses with the webs and shells in vertical alignment and a protective lining comprising hollow tile each coextensive in height with the tile of each course in the load bearing portion of the wall constituting a fireproof protection.

8. A fireproof wall structure, consisting of hollow load bearing tile walls in which the tile are arranged in horizontal courses with the webs and shells in vertical alignment, a lining comprising hollow tile coextensive with each course of load bearing tile, constituting a fireproof protection, and consisting of commensurate courses of blocks, securing elements extending into the mortar beds of the body of the wall and extending into the mortar beds of the lining, and means consisting of metal supporting strips extending parallel with certain of the courses in the wall, and spaced at vertical intervals and projecting into the horizontal mortar space of the lining courses, permitting the removal and replacement of the sections above or below such supports without disturbing the adjacent sections.

9. A fireproof structure, in which the main body of the wall consists of hollow tile arranged in horizontal courses and a fireproof protection for said wall consisting of a lining consisting of voided blocks, each having a height equivalent to a course and co-extensive with each complete course, and means bonding said lining to the wall with the lining blocks spaced from the wall consisting of elements embedded in mortar and extending from the body of the wall into the joint between the lining blocks.

10. A fireproof structure, in which the main body of the wall consists of hollow tile arranged in courses, and a fireproof protection for said wall consisting of a lining of voided blocks, each having a height

equivalent to a course and arranged to be co-extensive with each course, and means bonding said lining to the wall with the lining blocks spaced from the wall consisting

- 5 of elements embedded in mortar and extending from the body of the wall into the joints between the lining blocks, said blocks being divisible into the elements to facilitate fitting into the offsets, corners, and jambs of the wall, and the entire lining being adapted to be removed and replaced without disturbing the load bearing characteristics of the wall.

- 11. A fireproof structure, in which the main body of the wall consists of hollow tile arranged in horizontal courses, and a fireproof protection for said wall consisting of a lining consisting of voided blocks, each having a height equivalent to a course, said blocks being divisible into the elements to facilitate fitting into the offsets, and the entire lining being adapted to be removed and replaced without disturbing the load bearing characteristics of the wall, said lining extending around the window and door openings, and means by which the blocks

are supported under arches and lintels, consisting of upright connections extending up to and engaging the wall course or lintel above.

30

12. A fireproof wall structure, for a building, consisting of hollow load bearing tile walls in which the tile are arranged in horizontal courses, a protective lining of courses of hollow blocks arranged to be co-extensive with each course of the tile in the wall and constituting a fireproof protection therefore, and consisting of commensurate courses of blocks having a height such as to permit securing to the wall at 40 the mortar beds of the body of the wall, metal supporting strips extending parallel with certain of the courses in the wall and spaced at vertical intervals and projecting into the horizontal mortar space of the lining courses to support lining courses above, permitting the removal and replacement of the sections above or below such supports without disturbing the adjacent sections.

35

In testimony whereof, I hereunto affix 45 my signature.

FREDERICK HEATH.
